CLAIM

We claim the ornamental design for a device holder, as shown and described.

DESCRIPTION

FIG. 1 is a perspective view of a device holder showing the new design;

FIG. 2 is a front view thereof;

FIG. 3 is a back view thereof;

FIG. 4 is a side view thereof;

FIG. 5 is an opposite side view thereof;

FIG. 6 is a top plan view thereof;

FIG. 7 is a bottom plan view thereof;

FIG. 8 is a front view showing the design of FIG. 1 in a first alternate environment;

FIG. 9 is a front view showing the design of FIG. 1 in a second alternate environment;

FIG. 10 is a front view showing the design of FIG. 1 in a third alternate environment;

FIG. 11 is a front view showing the design of FIG. 1 in a fourth alternate environment; and,

FIG. 12 is a front view showing the design of FIG. 1 in an fifth alternate environment.

The broken lines appearing in the drawings represent unclaimed environment and form no part of the claimed design.

1 Claim, 12 Drawing Sheets
